THERMAL TIME DELAY RELAY

Arthur L. Bastian, Yonkers, N. Y., assignor to Curtiss-Wright Corporation, a corporation of Delaware

Application January 10, 1957, Serial No. 633,451

6 Claims. (Cl. 200—122)

This invention relates to thermal time delay relays of the kind in which a bimetallic element responsive to a heater actuates a switching member, and in which a second bimetallic member is employed to compensate for ambient temperature changes.

Thermal time delay relays of the character described have been found to vary considerably in time delay operation even though of apparently identical construction. As a given relay is cycled through its intended ambient temperature range, hysteresis effects have been observed; i. e. the time delay at a given ambient temperature has been found to be non-repeatable, as where the relay is first tested at an initial ambient temperature, next at a different ambient temperature and again at the initial ambient temperature, next at a different ambient temperature and again at the initial ambient temperature.

It is an object of the invention to provide an improved relay structure which is effective in minimizing hysteresis effects.

Another object of the invention is to provide an improved relay structure effective to minimize response variations from relay to relay.

In general bimetal strips are subject to two warping effects. The principal and desired effect takes place about an axis transverse to the major longitudinal axis of the strip and results in a cantilever or spiral deformation responsive to temperature changes. The second and undesired warping effect takes place about the longitudinal axis of the bimetal and results in a "cross-bowing" deformation. The two effects are interdependent as increased cross-bowing results in reduced bimetal activity, i. e. reduced principal cantilever deformation. In relays heretofore known the securing means have been depended on to determine both the fulcrum line for the principal warping effect of the bimetal member and also to restrain cross-bowing. The extent of cross-bowing restraint had depended largely on the amount of stress due to the clamping action of the securing means and had varied radically owing to differences in clamping force and also due to imperfections in the securing means. Because of the aforementioned interdependence of the warping effect the extent of desired warping of the unsecured active portion of the bimetal has likewise varied considerably and uncontrollably so. Moreover the securing means have not provided a clearly defined fulcrum line for the principal warping of the bimetal member from relay to relay or even for a given relay with temperature cycling.

In accordance with the invention the bimetal strips are supported in cantilever fashion, but the secured end portions thereof are precluded from warping in the principal direction and also from cross-bowing in the transverse direction. This is accomplished by providing the secured portions with a pair of flanges which preclude cantilever deflection of the secured end portion. Moreover the ends of the flanges are disposed in a common plane extending transversely of the longitudinal extension of the bimetal member and this plane positively establishes a uniform and invariant fulcrum line for the principal warping of

2

the member. The portion immediately adjacent to the secured end portion is off set relative to the secured end portion and also to the major active portion and thus precludes cross-bowing of the secured portion.

For a better understanding of the invention, reference may be had to the following more detailed description considered together with the accompanying drawing in which like characters identify like parts and in which Fig. 1 is a perspective view of a relay embodying the invention, the relay being enclosed in an envelope shown partially broken away; Fig. 2 is an elevational view of the relay shown in Fig. 1 with the envelope omitted; Fig. 3 is a partly fragmentary front elevational view of the lower terminal portions of the bimetallic members in Figs. 1 and 2; Fig. 4 is a sectional view taken along the line 4—4 in Fig. 3; Fig. 5 is a partly fragmentary enlarged perspective view of the yoke and compensator bimetallic member generally shown as in Fig. 1 but separated for convenience in illustration; and Fig. 6 is a diagrammatic representation of the relay circuitry.

As shown in Fig. 1 the relay structure 12 is enclosed in an envelope consisting of a metallic base member 14 and a metallic cover member 16. The base 14 includes a circular disc portion 18 and a concentric circular portion 20 of somewhat larger diameter shouldered on disc 18. The cover 16 is generally in the form of a thin walled circular cylinder coaxial with the base and has a closing upper end wall 22, whereas its lower end is open to engage the base member 14. The outside of cover 16 is formed to a concave inward ring 23 towards the lower end thereof and the corresponding inner convex surface 24 is intended to snap over the shoulder 20 onto the disc member 18 for tight fitting engagement therewith and also with the shoulder 20. The envelope may be evacuated or filled with a gas, in which case first the junction of base 14 and cover 16 is hermetically sealed off by welding or soldering; next a vacuum or gas line is introduced through an opening in the wall 22, and finally the opening is sealed off as indicated at 25, also by welding or soldering.

The relay is intended to plug into a standard 7 pin miniature tube socket and to this end there are provided seven relatively rigid contact pins, numbered sequentially from 1 to 7 in a counterclockwise direction as viewed from above the base, and extending downwardly of the base 14 in spaced relation to one another. Referring to Fig. 6, in which the pins are numbered in the conventional clockwise sequence as viewed from below the base, the No. 1 pin is connected to the normally closed contact 26 by means of the connections 28. A heater winding 30 is connected across the Nos. 2 and 3 pins to which heater power from a suitable source may be applied. The No. 5 pin by means of the connection 31 is connected to an armature 32 to whose opposite sides contacts 34 and 36 (Fig. 2) are secured. Contact 36 normally makes a connection with the fixed contact 26 whereas contact 34 is intended upon heating of the heater 30 to make a connection to another fixed contact 38 which is connected to the No. 7 pin. The Nos. 4 and 6 pins are not used electrically. The relay may be operated as a single pole double throw switch by introducing a current at pin 1 and passing the current normally through pin 5 and alternately (when heater 30 is heated) through pin 7. The relay may also be operated as single pole normally closed by passing a current normally between pin 1 and pin 5. The relay may also be operated as single pole normally open, in which case circuit connections are brought to the No. 1 and No. 7 pins.

Referring to Fig. 2, pin 1 is structurally typical of all other pins except the Nos. 4 and 6 pins. It comprises a vertical portion 1a which extends from below the base 14, through an aperture in the base 14 and then above

the base 14 to the interior of the envelope. An insulating filler 39 (Fig. 1) seals the aperture and spaces the pin 1 from the base 14. In the interior of the envelope the pin 1 is bent inwardly as at 40 and then bent once more to vertical alignment so as to form an end portion 42. The end portion 42 is welded to the front end of a metallic bar 44. Bar 44 extends in parallel relation to an axial sectional plane (not shown) passing approximately mid-way between the No. 1 and No. 7 pins. The bar 44 is integrally formed with the fixed contact 26 which is approximately centered thereon and projects upwardly thereof. The Nos. 4 and 6 pins are provided solely for engagement in the mating members of the tube socket and for this reason they may be clipped off above the base 14 as shown. Otherwise they are structurally similar to the other pins. The internally off-set structure of the pins serves to space the relay structure 12 apart from and above the base 14 and also to support the relay structure 12 in fixed spatial disposition.

The relay structure 12 proper is arranged in a "stacked assembly" which comprises in order the following elements (Figs. 1 and 2); the compensator bimetal 48; a metallic strip 49; an annular insulating, spacing, and supporting member 50; a metallic bar 52; a similar annular insulating, spacing, and supporting member 54; the aforesaid bar 44; a still third annular insulating, spacing, and supporting member 56; and the actuator bimetallic member 58.

The lower ends of each of the stacked elements are disposed in substantially a common plane parallel to the base 14. The elements extend upward of the common plane in substantially parallel relation to one another with adjacent elements in mechanical contact and flush and clamping relation. The mechanical contact is assured by means of a fastening screw 60 which extends through apertures in the bars, the bimetallic members, and insulating spacers, and a therewith engaged nut 61 located on the outside of the compensator 48. The apertures in the bars 44 and 52 are sufficiently large to preclude contact with screw 60 and short-circuiting thereto. The strip 49 is welded onto the upper end of the No. 5 pin. The bar 52 in a fashion similar to that of bar 44 includes the fixed normally open contact 38 and is welded onto the upper end of the No. 7 pin. The bimetallic members 48 and 58 are of substantially rectangular strip form and extend upwardly of their fixed lower ends. They are arranged to warp in a counterclockwise direction responsive to a temperature increase and in a clockwise direction responsive to a temperature decrease.

In accordance with the invention the secured portions of the bimetallic members 48 and 58 and also the portions thereof immediately adjacent to the secured portions are deliberately deformed for positive definition of fulcrum lines. Referring to Figs. 3 and 4 each of the bimetallic members has an end portion 100 provided with an aperture 102 through which the screw 60 passes. The end portion terminates in a sharply defined line 103 which also marks the beginning of a relatively short intermediate portion 104 which extends obliquely and in offset relation to the end portion 100. Portion 104 terminates at a second sharply defined line 105 which also marks the beginning of the main active portion 106 of the bimetal member. Portion 106 extends upwardly of the stacked assembly and in parallel and off-set relation to the end portion 100. The arrangement is such that the central portions 104 extend laterally inwardly toward the center of the relay structure so that the active portions 106 are nearest to one another and the end portions 100 are farthest from one another.

The intermediate portion 104 is of narrower width than the main active portion 106 and has lateral edges 107 and 108 approximately equidistant from the respective lateral edges 109 and 110 of the active portion 106. The lateral ends of the end portion 100 are formed to

flanges 111 and 112 which extend outwardly of the stacked assembly and extend from the main section of the end portion 100 at approximately right angles and from a pair of sharply defined lines 113 and 114 which are continuous with respectively the lateral edges 107 and 108. The flanges terminate in a plane extending transversely of the longitudinal axis of the bimetal member, which plane passes through the line 103.

The flanges 111 and 112 preclude longitudinal spiraling of the secured end portion 100 and thus positively establish the line 103 as a uniform and invariant fulcrum line for the bimetallic member. By proper selection of the flange lengths the active length of the bimetal member may be conveniently adjusted and the deflection of the bimetal member and therefore the time delay controlled. The off-set intermediate portion 104 is in a sense another flange relative to the end portion 100 and as such precludes cross-bowing of the secured portion 100, thereby precluding variations in the activity of the intermediate and major portions due to inter-dependence of warping effects about mutually perpendicular axes. The portions 104 and 106 are subject to cross-bowing; however, as they are not restrained the cross-bowing effect is uniform. It is principally the secured portion 100 which is subject to non-uniformities due to non-uniformities in the securing means as explained hereinabove, but cross-bowing of portion 100 is precluded by flange-like restraining action of portion 104.

A self-locking nut 62 is mounted on the actuator 58, towards the upper end thereof. Nut 62 engages a screw 64 extending laterally of the actuator 58 with the screw head located approximately above the bar 52. The actuator 58 is provided with a pair of mica spacers 66 and 68 disposed on each side thereof. The heater 30, which may be made of Nichrome wire, is wrapped in several turns around the mica spacers 66 and 68 and its ends are connected by means of leads 70 and 72 which are welded respectively onto the upper ends of the No. 3 and No. 2 pins.

The connections 31 comprise the strip 49 and the compensator 48 which towards its upper end is bent laterally inwardly at approximately a right angle to form a bimetallic arm 74 integral with the main compensating portion 48. As is most clearly shown in Fig. 5, arm 74 is bifurcated towards its free end so as to form a pair of fingers 76 and 78 separated by a rectangular opening. Fingers 76 and 78 are provided at their lower surfaces with V-shaped notches which lend a knife-edge pivotal support to the armature 32. Said armature 32 is made of a thin sheet of planar metallic material, preferably copper for good conductivity, to the form of a U-shaped yoke with the upper ends of the stems of the U located within the notches in the member 74 and extending downwardly thereof approximately in parallel relation to the actuator and compensator. The U is completed by an interconnecting base portion 80 onto whose sides are mounted the movable contacts 34 and 36. The portion 80 is apertured above the contacts 34 and 36 and the lower end of a spring 82 is hooked through this aperture whereas its upper end is hooked onto the screw 64 adjacent the screw-head. The axis of the spring 82 is disposed substantially in the plane of the yoke 32. The screw 64 may be adjusted to vary the throw-over position of the spring 82 thereby controlling the time delay of the relay. Although the yoke is subject to compression it remains substantially planar throughout the range of operating temperature.

The switching means described is a snap-action mechanism as the armature or yoke 32 has no stable position in which neither of the fixed contacts 26 and 38 is engaged. In the particular arrangement described the spacing of contacts 26 and 38 is selected to provide one stable position absent heating of the heater 30, namely the normal position in which there is electrical continuity between pins 1 and 4 and pin 5. Continuity is provided

by the connections 28 which include the bar 44 to which the pin 1 is welded, then by contacts 26 and 36 and yoke 32, then by the support member 74 and the compensator 48 integral therewith, then by the bar 49 to the No. 5 pin welded thereto.

Actuator and compensator are arranged to warp with reference to supporting structure in a counterclockwise direction responsive to a temperature increase and in a clockwise direction responsive to a temperature decrease. The actuation of the yoke 32 depends only on relative displacement of the bimetallic members so that no switching takes place unless the heater 30 is energized by passage of current therethrough. In fact switching does not take place immediately but after a time delay subsequent to initial energization, i. e. after the heater 30 has heated sufficiently to cause the actuator to warp sufficiently to move the spring 82 overcenter with respect to the yoke fulcrum point thereby causing the yoke 32 to "snap over" and engage contact 38.

Because of the constructional features hereinbefore described, variations in time delay from relay to relay have been greatly minimized. Another beneficial effect of the improved relay structure has been minimization of hysteresis effects in cycling a given relay through its intended ambient temperature rating.

It should be understood that the preceding specification has been presented as an example of the invention and not as a limitation thereof, reference being had to the appended claims rather than to the preceding specification to determine the scope of the invention.

What is claimed is:

1. A thermal time delay relay having a high degree of uniformity in temperature response, comprising a base structure, an actuator bimetallic member and a compensator bimetallic member each of strip form, each of said members having an end portion secured to said structure, an intermediate portion extending from said end portion from a first sharply defined line and laterally and in off-set relation to said end portion, and a major active portion extending from said intermediate portion from a second sharply defined line and in off-set relation to said intermediate portion, the intermediate portion of each member being substantially narrower than the active portion thereof, said end portions being substantially non-responsive to temperature changes and the first sharply defined line of each bimetallic member defining a uniform fulcrum line for warping of the respective member, said relay further comprising switching means operatively related to said active portions and responsive to temperature difference therebetween, and a heater disposed in proximity to the active portion of said actuator for causing warping thereof about its said fulcrum line and operation of said switching means after a time delay.

2. A thermal time delay relay having a high degree of uniformity in temperature response, comprising a base

structure, an actuator bimetallic member and a compensator bimetallic member each of strip form, each of said members having an end portion secured to said structure that is provided with two flanges extending from said end portion respectively from first and second sharply defined lines and approximately at right angles, an intermediate portion extending from said end portion from a third sharply defined line and laterally and in off-set relation to said end portion, and a major active portion extending from said intermediate portion from a fourth sharply defined line and in off-set relation to said intermediate portion, said end portions being substantially non-responsive to temperature changes and the third sharply defined line of each bimetallic member defining a uniform fulcrum line for warping of the respective member, said relay further comprising switching means operatively related to said active portions and responsive to temperature difference therebetween, and a heater disposed in proximity to the active portion of said actuator for causing warping thereof about its said fulcrum line and operation of said switching means after a time delay.

3. A relay as specified in claim 1 wherein the intermediate portion of a bimetallic member has lateral edges that are approximately equidistant from respective lateral edges of the active portion of said member and wherein the end portion of said member is provided with a pair of flanges each extending from said end portion from a sharply defined line substantially continuous with a lateral edge of said narrower intermediate portion and at approximately a right angle.

4. A relay as specified in claim 2 wherein the intermediate portions of the bimetallic members extend towards one another from respective end portions.

5. A relay as specified in claim 3 wherein the intermediate portions of the bimetallic members extend towards one another from respective end portions.

6. A relay as specified in claim 1 wherein the intermediate portions of the bi-metallic members extend towards one another from respective end portions.
